United States Patent Office

Des. 225,163
Patented Nov. 21, 1972

225,163

ELECTRIC LAMP

Theodore Waddell, Via Rio Torto, Fiesole, Florence, Italy

Filed July 13, 1970, Ser. No. 23,927

Term of patent 14 years

Int. Cl. D26—04

U.S. Cl. D26—8

The figure is a perspective view of an electric lamp showing my new design.

The filament of the electric lamp is shown in broken lines for illustrative purposes only.

I claim:

The ornamental design for an electric lamp, substantially as shown and described.
